United States Patent Office

Des. 232,022

Patented July 9, 1974

232,022

FOOT-OPERATED JUVENILE VEHICLE

Joseph C. Tieri, Minneapolis, Minn., assignor to Leisure Dynamics, Inc., Minneapolis, Minn.

Filed Apr. 13, 1973, Ser. No. 350,731

Term of patent 14 years

Int. Cl. D12—11

U.S. Cl. D12—112

Fig. 1

Fig. 2

Fig. 3

Fig. 4Fig. 5Fig. 6FIG. 1 is a top, front, and left side perspective view of a foot-operated juvenile vehicle showing my new design;

FIG. 2 is a top plan view thereof;

FIG. 3 is a left side elevational view thereof, the right side being substantially a mirror image thereto;

FIG. 4 is a bottom plan view thereof;

FIG. 5 is a front elevational view thereof;

FIG. 6 is a rear elevational view thereof.

I claim:

The ornamental design for a foot-operated juvenile vehicle, as shown and described.
